SECTIONAL CONNECTED READING AND RECITATION TABLE

Oscar H. Steene and Annabelle Steene,
Twin Falls, Idaho

Application March 17, 1952, Serial No. 276,968

1 Claim. (Cl. 311—4)

1

This invention relates to sectional tables.

An object of this invention is to provide a sectional table which is formed of at least two semi-U-shaped sections which when assembled form a U-shaped table. This U-shaped table is designed as an instruction table whereby pupils may be seated about the outside of the table, and the instructor may be seated inside the table in a position to give close attention to any one or more of the pupils.

Another object of this invention is to provide a sectional table wherein the sections may be nested together, or placed one on top of the other, so as to reduce the space occupied by the table when not in use.

A further object of this invention is to provide an improved sectional table with means for detachably locking the table sections together.

With the above and other objects in view, our invention consists in the arrangement, combination and details of construction disclosed in the drawings and specification, and then more particularly pointed out in the appended claim.

In the drawings:

Figure 1 is a plan view of a sectional table constructed according to an embodiment of this invention.

Figure 2 is a detailed side elevation of the table.

Figure 3 is a fragmentary rear elevation of the table.

Figure 4 is a fragmentary sectional view taken on the line 4—4 of Figure 1.

Figure 5 is a fragmentary sectional view taken on the line 5—5 of Figure 1.

Figure 6 is a fragmentary sectional view taken on the line 6—6 of Figure 1.

Figure 7 is a fragmentary sectional view taken on the line 7—7 of Figure 1.

Figure 8 is a fragmentary sectional view taken on the line 8—8 of Figure 4.

Referring to the drawings, the numerals 10 and 11 designate generally a pair of table sections which are of substantially J configuration in plan and when connected together, form a substantially U-shaped table. The table sections 10 and 11 are of like construction and each section is formed of a top member 12, having legs 13 and 14 at the ends thereof and an intermediate leg 15 at substantially the junction between the straight portion and the arcuate portion thereof. The legs 13, 14 and 15 are double thickness plywood, and the top 12 is secured to the upper ends of the legs by means of fastening devices 16.

The top 12 includes a covering 17 which is secured by adhesive or the like to the plywood 18,

2

forming the top and, as shown in Figure 6, the covering 17 extends over the upper end of the leg 13, as indicated at 19. The end legs are rabbeted, as indicated at 20, and a moulding strip 21 is secured within the rabbet 20. This moulding 21 is also secured as by adhesive or the like to the marginal edges of the top 12.

A shelf 22 is disposed below the top 12, being secured in a channel 23 formed in the inner sides 10 of the legs, the shelf being fixedly secured in the channel 23 by fastening means 24. There is at least one vertically disposed partition 25 disposed between each pair of legs, and the partition 25 is inset at the opposite ends thereof, as indicated at 26 and 27, in the shelf 22 and in the lower side of the top 12. Securing means 28 and 29 secure the partition 25 between the top 12 and the shelf 22.

Each leg has secured to the lower end thereof a truncated V-shaped foot member 30 having a tongue 31 secured in a mortice or channel 32 formed in the lower end of the leg.

In order to provide a means whereby the confronting ends of the table sections 10 and 11 may be locked together, the inner leg 14 of table section 11 is formed with a wedge-shaped channel 33 at a point below the shelf 22, and the leg 14 is reduced in thickness above the channel 33, as indicated at 34. The inner end of the table section 10 is formed with a short leg 35 having a wedge-shaped lower end 36 engageable in the channel or keeper 33.

In order to provide a means whereby the confronting ends of the table sections may be held against horizontal movement, we have provided a key 37 which is secured as by fastening devices 38 to the outer side of the leg member 35, and key 37 engages in a vertically disposed keeper 39 which is formed in the reduced leg portion 34 of leg member 14. The inner ends of the table sections 10 and 11 are locked together by disposing the inner ends in close confronting position and then raising the inner end of table section 10 a sufficient distance to permit the locking wedge member 36 to engage within the keeper or channel 33. At this time, locking member 37 will be disposed in the keyway or keeper 39.

The sectional table hereinbefore described is adapted to be made out of plywood of suitable thickness and width with cover 17 secured to the top member 12. In the unassembled condition of the table sections, one of these sections may be disposed upside down on the other section with the tops in confronting position.

The table sections are locked together by means

of the complementary wedging members 33 and 36 and locking member 37. Where the table is used for instructing children or the like, the children will be disposed on the outer side of the table, and the instructor or teacher will be disposed between the parallel sides of the table. In this position, the instructor will be very close to all of the students so that they may be given substantially individual attention. This sectional table may also be used in libraries or other locations where a relatively large table surface is desired within a relatively confined location.

We do not mean to confine ourselves to the exact details of construction herein disclosed, but claim all variations falling within the purview 15 of the appended claim.

What is claimed is:

A sectional table having a U-shape in plan comprising a pair of table sections, each section being formed of a top member having a straight 20 portion and an arcuate portion extending from one end of said straight portion, a vertical leg at each end of said straight portion, said legs having a width equal to the width of said top, a leg fixed to one of said top members at the 25 free end of one of the arcuate portions thereof, said one leg having a horizontally disposed V-shaped keeper channel adjacent the upper end

thereof, a short leg fixed to the other of said top members at the free end of the arcuate portion thereof, a V-shaped locking member formed on the lower end of said short leg engageable in said keeper channel for locking said sections against movement in a plane at right angles to the confronting faces of said one leg and said short leg, and cooperative positioning means carried by said one leg and said short leg for locking said one leg and said short leg against movement in a plane parallel to the confronting faces thereof.
